UNITED STATES PATENT OFFICE.

SAMUEL T. THORPE, OF BRISTOL, CONNECTICUT, ASSIGNOR TO THE HORTON MANUFACTURING COMPANY, OF BRISTOL, CONNECTICUT, A CORPORATION OF CONNECTICUT.

GOLF CLUB.

Application filed July 14, 1922. Serial No. 574,906.

To all whom it may concern:

Be it known that I, SAMUEL T. THORPE, a citizen of the United States, residing at Bristol, in the county of Hartford and State 5 of Connecticut, have invented certain new and useful Improvements in Golf Clubs; and I do hereby declare the following to be a full, clear, and exact description of the same, reference being had to the accompanying drawings, forming a part hereof.

This invention relates to golf clubs and more particularly to the method of securing the shaft of the club to the club head, the invention being especially applicable to golf 15 clubs having hollow or tubular metallic shafts, although certain features of the invention may well be utilized in connection with clubs having solid wooden shafts.

An object of the invention is to secure the 20 metallic shaft in the head so that rotation of the head on said shaft is prevented by means that will have practically no tendency to split or otherwise damage the club head.

As the invention is especially applicable 25 to clubs having hollow metallic shafts, the invention further consists in the provision of a fastening device embodying means for preventing collapse of said shaft.

With these and other objects in view the 30 invention consists in certain novel details of construction, combinations and arrangements of parts, all as will hereinafter be more fully described and the novel features thereof particularly pointed out in the appended claims.

In the accompanying drawings—

Figure 1 is an elevational view of a golf club illustrating the preferred embodiment 40 of the present invention, a portion of the club head being broken away for purposes of illustration;

Fig. 2 is a bottom plan view of the club head;

Fig. 3 is a detail sectional view on the 45 line 3—3 of Fig. 2;

Fig. 4 is a detail view of the several fastening elements and the lower end of the shaft all removed from the club head and separated one from the other, and

50 Fig. 5 is a similar view, in perspective, showing the same parts assembled.

The club used for illustrating the invention is of the type known as the driver and has a wooden head 10 which is provided

with the usual striking face 11 on one of its 55 sides. Toward its rear end the head 10 is provided with the usual upwardly extending shank 12, known as the hosel, and extending down through the hosel and head to the bottom face of the latter is a circular aperture 60 for the reception of the shaft 13 which is preferably made tubular from a sheet of suitable metal and which extends down to the hosel and head with its lower end flush with the bottom face of said head.

At its lower end said shaft has two longitudinally extending slots 14 therein preferably located diametrically opposite each other for the reception of a key 15 whose sides project beyond the exterior surface of 70 shaft 13 into the head, which is usually and preferably slotted at points diametrically opposite each other in the shaft opening to permit the easy insertion of the key. Preferably key 15 is made perfectly flat, especially at its side edges where it projects into the head 10 for the purpose of presenting a plane, flat surface to the head when the latter is placed under strains tending to rotate it on the shaft. By making the key flat, or at least flat at its projecting side edges, it does not have any tendency to split the head whereas such would not be the case if the key were tapered or otherwise similarly shaped instead of being flat.

To aid in securing the key and shaft end 85 in the club head, wedge members 16 preferably of wood and substantially semi-circular in cross section at their larger end, are driven into the hollow shaft on each side of the key. Such wedges not only assist in holding the key and shaft in place but they also serve the function of supporting the hollow shaft from its interior, thereby preventing the collapse of the shaft.

As a final fastening means for securing the wedges, shaft and key in the head, a screw 17 or other like fastening member, projects into the club head from the rear face of the latter and extends at substantially right angles to the shaft 13, through the shaft, the wedges and the key, said shaft and key having apertures 18, 19 therein adapted to register with each other for the screw to be passed therethrough.

It will be understood that, in the finished golf club, the lower ends of the shaft, key and wedges, terminate flush with the bottom

face of the head and said bottom face can be finished off the same as any ordinary club.

What is claimed is:

1. In a golf club, the combination with the head and shaft extending into said head, of a flat key extending transversely of the shaft and projecting beyond the side faces of said shaft into the head.
2. In a golf club, the combination with the head, of a metallic shaft extending into the head, said shaft being hollow within the head, a key extending transversely of the hollow portion of the shaft and projecting transversely into the club head, and means preventing collapse of the hollow portion of the shaft.
3. In a golf club, the combination of the head, a metallic shaft having a hollow end portion extending into the head and there being longitudinally extending slits in said hollow end portion, and a key positioned transversely of the shaft in said slits and projecting beyond the side faces of the shaft into the head.
4. In a golf club, the combination of the head, a metallic shaft having a hollow portion extending into the head, a key extending transversely of the hollow portion of the

shaft and projecting into the head, means for preventing collapse of the hollow portion of the shaft, and fastening means extending into the head at an angle to the shaft and through the hollow portion of the shaft.

5. In a golf club, the combination of the head, a metallic shaft having a hollow portion extending into the head, a key extending transversely of the hollow portion of the shaft and projecting into the head, wedging members between said key and the interior walls of the hollow portion of the shaft, and fastening means extending into the head and through the shaft and engaging said wedging members.

6. In a golf club, the combination of the head, a metallic shaft having a hollow portion extending into the head, a flat key having parallel side faces at its end portions, said key extending transversely of the hollow portion of the shaft and its end portions projecting into the head, wedging members between said key and the interior walls of the hollow portion of the shaft, and fastening means extending into the head and engaging said key and wedging members.

SAMUEL T. THORPE.
